UNITED STATES PATENT OFFICE.

JOHN W. FREEMAN, OF ALLEENE, ARKANSAS, ASSIGNOR OF ONE-HALF TO SQUIRE C. HODGES, OF ARDEN, ARKANSAS.

NON-REFILLABLE BOTTLE.

1,082,020.

Specification of Letters Patent. Patented Dec. 23, 1913.

Application filed September 12, 1911. Serial No. 648,931.

To all whom it may concern:

Be it known that I, JOHN W. FREEMAN, a citizen of the United States, residing at Alleene, in the county of Little River and 5 State of Arkansas, have invented a new and useful Non-Refillable Bottle, of which the following is a specification.

It is the object of this invention to provide a bottle having a stopper consisting of 10 primary and secondary parts, the construction being such that when the primary part is withdrawn, the secondary part will drop to the bottom of the bottle, it being impossible to remove the secondary part, the said 15 secondary part, when free to move within the bottle, serving to indicate that the bottle has been filled and emptied. The device, therefore, aims to provide a bottle which will indicate when it has been once emptied.

20 With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

30 In the accompanying drawings,—Figure 1 shows the preferred form of the invention in longitudinal section; Fig. 2 is a fragmental longitudinal section showing the tip of the stopper broken off, the device being 35 shown in Fig. 2 as it will appear after it has been filled, and still contains its contents; Fig. 3 is a transverse section upon the line A—B of Fig. 1; Fig. 4 is a perspective of the secondary member of the stopper; 40 Fig. 5 is a longitudinal section showing a modified form of invention; and Fig. 6 is a perspective of the secondary portion of the stopper which is employed in connection with that form of the invention which appears in Fig. 5.

In carrying out the invention there is provided as a primary and fundamental element, a receptacle 1, which may be of any form. In the present instance, the receptacle 1 is shouldered at its upper end, as shown at 2, and is provided with a neck 3.

The stopper is a two-part structure, and includes a primary member 4, adapted to fit closely in the neck 3. The primary member 4 is preferably fashioned from cork.

The secondary member of the stopper consists of a head 5 and an upstanding, tapered, conical neck 6. The head 5 is adapted to engage the shoulder 2 of the receptacle, and the neck 6 is adapted to be wedged in the 60 annular primary member 4.

The upper end of the neck 6 is flush with the outer end face of the primary member 4. The secondary member, comprising the parts 5 and 6, is preferably fashioned from 65 glass, and includes a frangible tip 7, formed at the outer end of the neck 6, the tip 7 being constricted adjacent its point of union with the neck 6, as shown at 8. The tip 7 terminates in a boss 9, adapted to receive a 70 cord 10, a wire or other flexible element.

In that form of the invention which appears in Fig. 5, the bottle or receptacle is denoted by the numeral 11, the same being shouldered as shown at 12, and being provided with a neck 14.

The stopper is a two-part structure, as before, and comprises an annular part 15, preferably fashioned from cork, and adapted to fit closely in the neck 14. The secondary member of the stopper consists of a head 16, adapted to engage the shoulder 12. Fixed to and protruding from the head 16, is a neck 17, the outer end of which is substantially flush with the outer end face of 80 the primary member 15 of the stopper. A flexible element, preferably a wire 18 is secured to the outer end of the neck 17.

The operation of that form of the invention which appears in Fig. 1 is as follows: Since the secondary member, comprising the parts 5 and 6, cannot be removed through the neck 3, this secondary member is of course placed within the bottle 1, while the same is being manufactured. By inverting the bottle, the secondary member may be positioned substantially as shown in Fig. 1. Under such circumstances, the tip 7 will protrude beyond the end of the neck 3, and therefore a hold 90 may be secured upon the tip 7. The flexible element 10 is then secured to the tip 7, this flexible element 10 being threaded through the central opening in the primary part 4. The primary and secondary parts are then assembled in the neck of the bottle 3, as shown in Fig. 1, and the tip 7 is broken off at its grooved portion 8, the device under such circumstances appearing 100 substantially as indicated by the reference 110

105

character 28 in Fig. 2. When the primary member 4 is removed, in order to permit a pouring out of the contents of the bottle 1, the head 5 of the secondary member will 5 engage the shoulder 2 and drop to the bottom of the bottle. Whenever, therefore, a customer receives a bottle 1, in which the secondary member is loose and rolling about, the customer may be assured that the bot- 10 tle has been refilled. Owing to the fact that the stem 7 has been broken off, after the first filling of the bottle, the primary and secondary parts of the stopper cannot be reassembled in their original positions. 15 That form of the invention which appears in Fig. 5 does not differ materially in operation from the foregoing, the wire 18 being clipped off close to the upper end of the neck 17, after the bottle has been filled. 20 In either form of the invention, the secondary member of the stopper is provided with a removable portion, facilitating the assembling of the primary and secondary parts, the removable portion being cut or 25 broken off, after the bottle is filled, whereby the primary and secondary portions of the stopper cannot again be assembled, after they once are separated. 30 It is to be noted that the bore of the neck of the bottle is tapered inwardly. Consequently, when the tapered part 6 of the secondary member of the stopper is thrust into the primary member of the stopper, a maximum compression will take

place in alinement with the top 2 of the 35 bottle. Therefore, a lateral bursting of the neck of the bottle, due to the transverse pressure of the part 6 will be avoided. Further, by reason of the construction above pointed out, the closure will fit tightly in 40 the neck adjacent the liquid.

Having thus described the invention, what is claimed is:—

In a device of the class described, a receptacle comprising a top, and a neck having a tapered bore, the narrowest portion of the bore being alined with the top; a cylindrical, compressible member located in the neck and extended across the plane of the top; and an inwardly removable stopper comprising an outwardly tapered extension, the widest part of the extension engaging the compressible member in alinement with the top and in alinement with the narrowest part of the bore of the neck, 50 to effect a maximum compression at the inner end of the cylindrical member and in alinement with the top, whereby the top will constitute a reinforcement, adapted to 55 resist the maximum compression.

In testimony that I claim the foregoing as my own, I have hereto affixed my signature in the presence of two witnesses.

JOHN W. FREEMAN.
